UNITED STATES PATENT OFFICE.

EDWARD A. PRATT, OF CHICAGO, ILLINOIS.

LOOSE-LEAF BINDER.

Application filed March 18, 1921. Serial No. 453,491.

To all whom it may concern:

Be it known that I, EDWARD A. PRATT, a citizen of the United States, a resident of Chicago, in the county of Cook and State 5 of Illinois, have invented new and useful Improvements in Loose-Leaf Binders, of which the following is a specification.

This invention has reference to loose-leaf binders, and relates particularly to the fastening means for detachably attaching the cover to the binder, and to a flexible pressure means on the under side of the cover at the binding margin of the binder to exert pressure on a few or more sheets secured in the 15 binder.

This invention has for a further object to improve the post-type binder by providing a fastening means for the top cover which is keyless, buttonless, and which has no protruding sections of posts; thereby leaving the top and bottom covers free of any projections or rough surfaces which would scratch, mar or damage the surfaces of desks, tables, etc.

25 A further object of the invention is to provide for post binders a locking means for securing the cover in place, which comprises a sliding plate adapted to have a locking engaging relation with the posts, so that when moved in one direction, it locks the cover in place and when moved in the opposite direction, it unlocks said cover. Said plate and posts being unexposed, except for 30 a portion of the length of the plate, which may be engaged by the thumb with the index finger bearing against either side edge of the binder to give the necessary leverage for the sliding of said plate in either direction.

40 A further object of the invention is to provide a binder with unexposed posts each having an annular groove, and a sliding plate adapted to be moved in one direction to enter in said grooves to lock the covers of 45 the binder, and when moved in the opposite direction, to be withdrawn from said grooves to release the top cover. Said posts and plate being unexposed, except for a portion of said plate at the rear marginal edge of 50 the binder, to permit a finger hold for sliding said plate.

A still further object of the invention is to combine with the locking means for the top cover of a post binder, a flexible pressure means, preferably a flat spring secured 55 to the under side of the top cover at the

binding portion thereof, which will lie against the sheets held between the covers of said binder. Such a plate will act to compress and firmly hold the sheets when there are less than enough to fill the depth of the posts between the covers and which will continue to act and yet flatten out as the binder is filled the full depth between the covers.

That the invention may be more fully understood, reference is had to the accompanying drawings forming a part of the present description, illustrating a preferred embodiment of the invention, in which:

Fig. 1 is a perspective view of an inexpensive post binder with my improved locking means and sheet holding means thereon.

Fig. 2 is a perspective view similar to Fig. 1 except that it shows the type of a more expensive binder, and with sheets secured 75 therein;

Fig. 3 is an enlarged plan view of the post end of said binder showing in full and dotted lines the locking means for the cover;

Fig. 4 is an end view of Fig. 3;

Fig. 5 is a cross-section as the same would appear if taken on the line 5-5 Fig. 4;

Fig. 6 is a perspective view of the sliding locking plate, and

Fig. 7 is an elevation of a post unit and 85 a screw therefor.

Like characters of reference denote corresponding parts throughout the figures.

The customary binder of the character referred to comprises the top and bottom covers 1 and 2 between which record sheets 3 are secured or bound. Both said covers have flexible portions 4 to provide a hinge for the raising or swinging back of the cover 90 that the binder may be opened to give access to the sheets 3. From the flexible part 4 of the top cover 1 to the rear marginal edge of the binder is referred to as the securing or marginal binding portion of said binder.

Secured in any suitable manner to the 100 marginal binding part of the lower cover 2, in spaced relation and extending up therefrom, are binding posts 5. These posts are usually made in several detachable sections, to be built up one on the other to 105 provide for more and more sheets to be added to the binder. The post 5 is the first or initial section of suitable height and at its upper end this post section is provided or formed with an annular groove 110 6 and with a threaded opening 7 leading thereto from the upper end, to receive

the lower threaded end of the next adjacent post section or extension, and a cap screw 8 with an annular groove 9 is used for the immediate top section.

5 The top cover 1 is provided with openings 10 thru which protrude the posts 5 when the top cover is put into place over said post, but the upper ends of said post are not exposed to view because of the 10 cover plate 11, in the form of an inverted U channel, with closed opposite ends, placed on and extending the full width transversely across the top cover 1 at the marginal binding edge of the binder. In Fig. 15 1 this cover plate is preferably an exposed metal plate, whereas in Fig. 2 the plate is preferably covered with cloth or some other suitable material which is also used to cover the top cover 1 making it appear 20 as a unitary structure. Said channel cover plate is cut out at the marginal edge of the binder, as at 12, for a portion of its length to expose an engaging portion of a locking plate 13 slideable in the channel plate 25 and on the top of the top cover 1. This plate 13 is best seen in Figs. 2, 3, and 6 and is shown along one edge as being formed or provided with a finger hold 14, and guiding flanges 15 to bear and slide against 30 the rear wall of the channel plate 11, see Figs. 3 and 5. The opposite or front edge of said plate 13 is formed or provided with a central or intermediate flange portion 16 to bear and slide against the front wall of 35 said channel plate 11, see also Figures 3 and 5, and from said flange 16 to the outer or opposite ends of said plate the same is formed or provided with wedges 17. The finger hold 14 constitutes a flange, as shown, 40 and it bears and rides against the edge of the cut out portion 12 of said channel plate. It will thus be observed that the flanges 14, 15 and 16 as they bear against surfaces of the channel plate 11 hold and confine 45 the plate 13 to its work, and that while the finger hold portion of said plate is exposed, it is confined within the space occupied by the outside walls of the channel plate 11, and that therefore it does not 50 protrude so as to mar the surface of a desk, table, etc.

When the top cover is in assembled position on the lower cover, by placing the index finger in the finger hold 14 on the plate 55 13 and the thumb against the left hand edge of the binder, looking at Fig. 3, and moving the plate 13 to the left, the wedges 17 will enter the grooves 6 in the posts 5 and frictionally impinge said posts to lock 60 the top cover in place. In similar manner, if the thumb is inserted in the finger hold 14 and the index finger is caused to bear against the right hand edge of the binder, looking at Fig. 3, and the plate 13 is moved 65 to the right, the wedges 17 are withdrawn

from the grooves 6 in the posts 5 and out of impinging relation with said posts, releasing the top cover so that it may be removed from the binder.

To the under side of the top cover 1 and 70 immediately below the locking plate 13 is riveted or otherwise suitably secured a spring plate 18 which is disposed transversely of the binder and with the opposite ends curved downwardly and outwardly to 75 bear against any sheets placed between the covers of the binder, as shown in Figs. 2 and 4. This spring functions to secure the sheets in a compact manner when there are but a few sheets in the binder, and as 80 the binder is filled the spring flattens out, however, continuing to function as a securing and compressing means for the sheets.

With my improved keyless, buttonless and non-protruding cover securing means, I am 85 able to construct the binder with a comparatively narrow plate 11 at the binding margin and locate the posts close to the front transverse edge of said plate, in manner 90 shown in the drawings.

95 What I claim is:

1. In a binder of the character described, in combination, top and bottom cover members, posts upstanding from the bottom cover member, the top cover member having openings to receive said posts, a closure on the top cover to enclose the upper ends of said posts, and cut away for a portion of its length along the rear marginal edge of the binder, and a slideable plate within said closure adapted to have an impinging locking relation with said posts, and having an exposed finger hold portion coincident with the cut away portion of said closure. 100

105 2. In a binder of the character described, in combination, top and bottom cover members, posts upstanding from the bottom cover member provided with annular grooves at their upper ends, the top cover member having openings to receive said posts, a closure on the top cover to enclose the grooved ends of said posts and cut away for a portion of its length along the rear marginal edge of the binder, and a slideable plate within said closure having opposite end wedges adapted to enter the grooves in said posts and have an impinging locking relation with the bodies of said posts, and having an exposed finger hold portion coincident with the cut-away portion of said closure. 110

115 3. In a binder of the character described, in combination, top and bottom cover members, posts upstanding from the bottom cover member, the top cover member having openings to receive said posts, a closure on the top cover to enclose the upper ends of said posts, and cut away for a portion of its length along the rear marginal edge of the binder, a slideable plate within said closure 120

adapted to have an impinging locking relation with said posts, and having an exposed finger hold portion coincident with the cut away portion of said closure, and a flexible sheet engaging member secured to the underside of said top cover member immediately below said closure.

4. In a binder of the character described, in combination, top and bottom cover members, posts upstanding from the bottom cover member provided with annular grooves at their upper ends, the top cover member having openings to receive said posts, a closure on the top cover to enclose the grooved ends of said posts and cut away for a portion of its length along the rear marginal edge of the binder, a slidable plate within said closure having opposite end wedges adapted to enter the grooves in said posts and have an impinging locking relation with the bodies of said posts, and having an exposed finger hold portion coincident with the cut away portion of said closure, and a flexible sheet engaging member secured to the underside of said top cover member immediately below said closure.

5. A locking means for a post binder, comprising a plate stamped out of a single sheet of metal and formed with opposite wedge ends spaced by an upstanding guiding flange, and flanges along the opposite edge one of which is indented to provide a finger hold portion.

6. In a post binder, in combination with the posts locking means comprising a sliding plate formed with an intermediate finger hold portion along one edge and guiding flanges on either side of said finger hold portion, and a guiding flange and spaced wedging portions on the opposite edge of said plate, said wedging portions adapted to have an impinging locking relation with said posts.

7. In a post binder, in combination, posts

provided with annular grooves at their upper ends, and a sliding plate having a finger hold portion on one edge, and wedging portions on its opposite edge adapted to enter the grooves in said posts and also have an impinging locking relation with said posts.

8. In a post binder, in combination, posts provided with annular grooves at their upper ends, a cover plate for the upper ends of the posts comprising an inverted U channel bar, the edge of said plate coincident with the margin of the binder being cut away for a portion of its length, a plate slidably carried within the channel of said cover plate and having guiding flanges lying and movable along the sides of said cover plate, a finger hold on said slidable plate coincident with the cut away portion of said cover plate, and wedging means on said slidable plate adapted to enter the grooves in said posts and also to have an impinging locking relation with said posts.

9. In a post binder, in combination, posts provided with annular grooves at their upper ends, a cover plate for the upper ends of the posts comprising an inverted U channel bar, the edge of said plate coincident with the margin of the binder being cut away for a portion of its length, a plate slidably carried within the channel of said cover plate and having guiding flanges lying and movable along the sides of said cover plate, a finger hold on said slidable plate coincident with the cut away portion of said cover plate, wedging means on said slidable plate adapted to enter the grooves in said posts and also to have an impinging locking relation with said posts, and a flexible sheet engaging member secured to said binder immediately below said cover plate.

In witness whereof, I have hereunto affixed my hand this 7th day of March, 1921.

EDWARD A. PRATT.
